(57) **CLAIM**

The ornamental design for a crab opening tool, as shown and described.

DESCRIPTION

FIG. 1 is a front elevational view of a crab opening tool showing my new design;

FIG. 2 is a rear elevational view thereof;

FIG. 3 is a left side elevational view thereof;

FIG. 4 is a right side elevational view thereof;

FIG. 5 is a top plan view thereof;

FIG. 6 is a bottom plan view thereof;

FIG. 7 is a left side perspective view thereof;

FIG. 8 is a right side perspective view thereof;

FIG. 9 is a perspective view showing a left side section of the present invention;

FIG. 10 is a perspective view showing a right side section of the present invention; and,

FIG. 11 is an exploded perspective view of the present invention.
